UNITED STATES PATENT OFFICE.

FRANK B. KECK AND HENRY A. LUDWIG, OF CLEVELAND, OHIO, ASSIGNORS TO THE HOMER COMMUTATOR COMPANY, OF CLEVELAND, OHIO, A CORPORATION OF OHIO.

RIVETING-MACHINE.

1,197,828.

Specification of Letters Patent. Patented Sept. 12, 1916.

Application filed July 27, 1915. Serial No. 42,200.

To all whom it may concern:

Be it known that we, FRANK B. KECK and HENRY A. LUDWIG, citizens of the United States, residents of Cleveland, county of 5 Cuyahoga, and State of Ohio, have invented a new and useful Improvement in Riveting-Machines, of which the following is a specification, the principle of the invention being herein explained and the best mode in which 10 we have contemplated applying that principle, so as to distinguish it from other inventions.

Our invention relates to riveting machines, its object being to provide a riveting machine economical of manufacture and efficient in its operation.

The said invention consists of means hereinafter fully described and particularly set forth in the claims.

20 The annexed drawings and the following description, set forth in detail certain means embodying our invention, the disclosed means, however, constituting but one of various mechanical forms in which the principle of the invention may be applied.

The illustrated embodiment of our invention comprises a machine specifically adapted to rivet the ends of tubular members such as the inner sleeves of commutators, the 30 abutment members shown being arranged so as to properly receive and operate upon a commutator of standard construction.

In said annexed drawings:—Figure 1 represents a front elevation of a riveting machine embodying our invention, a portion of the abutment member being shown in vertical section, and a commutator constituting the work upon which the riveting operation is being performed being also shown in axial 40 section therein. Fig. 2 represents a view similar to that shown in Fig. 1, showing the parts in the position which they occupy while the machine is not in operation. Fig. 3 represents a side elevation of the machine 45 showing the parts in the same position in which they are shown in Fig. 2. Fig. 4 represents, upon an enlarged scale, an axial section of a commutator showing the parts assembled and in the condition in which 50 they are found prior to the riveting operation. Fig. 5 represents a view similar to that of Fig. 4 showing the parts after the riveting operation is completed. Fig. 6 represents a horizontal section taken upon the 55 plane indicated by line IV—IV in Fig. 1,

The illustrated embodiment of our invention comprises a base 1 to which are secured three vertical standards, two lateral standards 2, 2, and a rear standard 3. These standards are all parallel with each other, as 60 shown, and with the base constitute the main frame of the machine. The upper end of standard 3 is threaded as at 4 and secured thereto by means of nuts 5, 5, is an abutment member 6. The said standards 2, 2, have 65 their upper ends threaded which engage the threaded openings 7, 7, of the member 6, and extend upwardly beyond same a short distance, as shown in Fig. 1. Nuts 8, 8, lock this abutment member in position.

Secured on to the upper ends of the standards 2, respectively, are two members 9, 9, each of which is provided with an upwardly extending cylindrical portion 10, integral with the lower or threaded portion. These 75 two portions 10 are threaded at their upper ends at 11. Resting upon the shoulder 12 formed upon the members 9, respectively, are two loose tubes 13, 13, and resting upon the upper ends of these tubes is a cross-head 14, through suitable openings in which the portions 10, 10, of members 9 extend. Upon the upper or threaded ends 11 of the members 10 are the nuts 15, 15, respectively, and intermediately of each nut and the cross-head 14 is a coil spring 16, Fig. 1. This cross head has secured to it in any suitable manner a pneumatically operated hammer 17 of standard construction, the axis of the hammer being placed vertically, as shown. 90 This hammer is provided with the usual controlling member 18 forming part of a controlling valve mechanism for controlling the operation of the hammer, as will be readily understood.

It will be seen from the above construction that normally the cross-head 14 rests upon the upper ends of the tubes 13 and that by means of a force suitably applied from below, the cross-head and hammer carried 100 thereby may be caused to yield upwardly, thereby giving the controlling valve lever 18 a yielding movement in such upward direction, in addition to the yielding movement which it possesses in its direct actuation, as will be readily understood.

Secured in any suitable manner, so as to be fixed with relation to the frame, is an upwardly projecting strap 19, Figs. 1 and 3. This strap is shown secured to the upper 110

surface of the abutment member 6, and extends upwardly beyond the lever 18 of the hammer, its extreme upper portion 20 being provided with an adjustable screw member 21, the lower end of which lies in the path 5 of yielding movement of the said lever, when such movement is imparted to the hammer and said lever, as will be herein-after described.

10 Suitably secured to the frame and having its vertical axis in alignment with the axis of the hammer 17, is a cylinder 22 provided with a suitable piston (not shown) and a piston rod 23. The upper end of this piston rod is formed with a seat 24 of an exterior 15 diameter equal to the interior diameter of the sleeve 25 of the commutator, so that the said sleeve may be received by and held against lateral displacement upon the upper 20 end of said piston rod. This piston rod therefore acts as a work-holder.

A guide-member 26 consisting of a suitable plate is provided with apertures 27 through which the side rods 2, 2, and rear 25 rod 3, extend, suitable set screws 28, 28, being provided to secure this guiding-member in place. The center of the guiding-plate is formed with a suitable bore 29, through which the piston rod 23 extends.

30 A pipe 30 is connected with a suitable source of compressed air supply (not shown) and has its upper end connected with a four-way valve 31. This valve is connected with a pipe 32 which in turn is connected with the upper end of the interior of cylinder 22 and hence above the piston. Another pipe 33 connects said valve with the lower end of the cylinder and below the piston. A third pipe 34 is connected with the valve 35

40 and acts as an exhaust pipe. This valve construction is old and well-known and constitutes no part of our invention. By turning the valve into the position shown in Fig. 6, compressed air is admitted above the piston in the cylinder and if such piston is in its elevated position, will cause it to move downwardly and the upper end of the piston rod 23 or work-holder, to recede from the abutment member 6. At the same time any 45 air below the piston will be expelled through the valve and out through the exhaust pipe 34, as will be readily understood. By throwing the valve into the position shown in dotted lines in Fig. 6, the piston and 50 work-holder may be elevated, as will be also readily understood. Connected with the pipe 33 is a flexible pipe 35 which is connected with the pneumatic hammer 17 at 36, in the usual manner, to supply the necessary fluid pressure to such hammer. It 60 will therefore be seen that when the valve 31 is turned to supply pressure to the pipe 33, similar pressure will be supplied to the pipe 35 and hence to the hammer.

65 Co-axial with the piston rod 23 and ham-

mer 17, is a cylindrical vertical opening 36, formed in the abutment member 6. Passing and projecting through this opening is a riveting tool 37 having its upper end formed with a flange 38 which rests upon the upper 70 surface of an upwardly projecting boss 39 forming part of the said abutment member, when the parts are in their inoperative position, shown in Fig. 2. The lower end of this tool is formed with a seat 40 adapted to 75 enter the upper end of the sleeve 25 of the commutator and forming a rounded concave shoulder 41 which constitutes the riveting surface of the tool. Surrounding the lower end of the opening 36 is an annular groove 80 42, Figs. 1 and 2, which is adapted to receive the upper end of the commutator and forms an annular shoulder 43 which is adapted to abut the commutator laterally of the upper end of the sleeve, as shown in Fig. 1. 85

When the parts are in their normal or inoperative position, shown in Fig. 2, the lower end of the tool 37 projects some distance beyond the lower end of the shoulder 43, as shown in Fig. 2.

90 The guide-member 26 is placed in a position such that when the piston is in its lower-most position in the cylinder 22, the upper or work-holding end of the piston rod 23 will project some distance above said member 26, as shown in Fig. 2.

95 The positions of the cross-head 14 and abutment member 7 are such that the lower end or head 44 of the hammer 17, will rest normally upon the upper end or head of the riveting tool 37. In this position, the lower end of the adjustable screw 21 is out of contact with the lever 18 of the controlling valve of the hammer.

100 We will now describe the operation of the above-described device.

The parts of the commutator are assembled as shown in Fig. 4, said parts including the inner sleeve 25 which is provided with the lower flange 25^a, it being desired now 110 to rivet the upper end of said sleeve so as to secure same permanently in place, as will be readily understood. The commutator parts so assembled are now placed upon the upper end of the piston rod or work-holder 115 23, when the latter is in its lowered position, as shown in Fig. 2, and the handle 31^a of the valve 31 turned so as to admit pressure below the piston in the cylinder 22, at the same time admitting, as previously described, the compressed air into the pipe 35. From this latter pipe the air may be admitted to the hammer so as to operate same, by the downward pressure of the lever 18 of the controlling valve thereof, as will be 120 readily understood. When the air is so admitted to cylinder 22, the piston rod 23 is carried upwardly, thus carrying the assembled parts of the commutator upwardly in a like manner. Such upward movement 125 130

finally causes the upper end of the commutator to engage the lower end of the riveting tool, the teat 40 entering the upper end of the bore of the sleeve 25. This upward movement continues and the riveting tool 37 is raised, thus raising the hammer 17 and the cross-head 14 against the action of the springs 16. This upward movement continues until the shoulder 43 engages the surface 25^b of the commutator, such surface being shown clearly in Fig. 4. The screw 21, however, is of a length such and is adjusted so that as soon as this engagement takes place, the lower end of said screw will have depressed the lever 18 so as to admit the pressure to the interior mechanism of the hammer and operate same. The hammer, therefore, delivers successive blows to the upper end of the loosely mounted riveting tool 37, and the riveting action takes place. This action is continued until the riveting operation is complete, whereupon the handle 31^a is turned so as to admit pressure above the piston and permit the air below same to be exhausted. In the initial portion of the downward movement of the piston rod, the riveting tool 37 follows the commutator until the head 38 is again in contact with the upper surface of boss 39, the hammer 17 and cross-head 14 likewise moving downwardly. This causes the controlling valve lever 18 to assume its normal position and cut off the supply of air from the hammer, the latter thereby ceasing its operation. When the piston rod reaches its lowermost position, the commutator is removed, and the above-described operation may then be repeated.

It will therefore be seen that the above-described device comprises an efficiently operating riveting mechanism in which the valve 31 and the valve controlled by the lever 18 together form means for controlling both the riveting hammer and the movement of the work-holder toward the abutment member, the valve 31 controlling the supply of air pressure to both the hammer and the cylinder 22, the valve mechanism of which the handle 18 forms a part controlling, however, the operation of the hammer alone. In this mechanism, the means for controlling the operation of the riveting hammer is itself controlled by the yielding movement of the latter, in opposition to the springs 16, the work-support imparting the yielding movement to the hammer.

Having fully described our invention, what we claim and desire to secure by Letters Patent is:—

1. In a riveting machine, the combination of a suitable frame; an abutment-member mounted upon the latter; a work-support relatively movable toward and from said abutment-member; a riveting device coöperating with said work-support; means for

operating said riveting device; means for actuating said work-support; and means for controlling the operation of said riveting device and the actuation of said work-support.

2. In a riveting machine, the combination of a suitable frame; an abutment-member fixed to and adjustable upon the latter; a work-support relatively movable toward and from said abutment-member; a riveting device mounted upon said frame and coöperating with said work-support; means for operating said riveting device; means for effecting the relative movement of said work-support and abutment-member; and means for controlling the operation of said riveting device and the actuation of said work-support.

3. In a riveting machine, the combination of a suitable frame; a stationary abutment member mounted upon the latter; a work-support relatively movable toward and from said abutment member; a riveting device coöperating with said work-support and yieldingly mounted upon said frame; means for controlling the said relative movement; and means for controlling the operation of said riveting means and itself controlled by the yielding movement of the latter.

4. In a riveting machine, the combination of a suitable frame; an abutment member mounted upon the latter; a work-support relatively movable toward and from said abutment member; a riveting device coöperating with said work-support and mounted upon said frame and adjacent to that side of said abutment member opposite that adjacent to which said work-support is mounted; and means for controlling the operation of said riveting device and the relative movement of said work-support.

5. In a riveting machine, the combination of a suitable frame; an abutment member mounted upon the latter; a work-support relatively movable toward and from said abutment member; a riveting device coöperating with said work-support and yieldingly mounted upon said frame and adjacent to that side of said abutment member opposite that adjacent to which said work-support is located; means for controlling said relative movement; and means for controlling the operation of said riveting means and itself controlled by the yielding movement of the latter, said work-support being adapted to impart the yielding movement to said riveting device.

6. In a riveting machine, the combination of a suitable frame; an abutment member secured to the latter; a work-support and fluid-pressure means for actuating same toward and from said abutment member; a fluid-pressure operated riveting device coöperating with said work-support and mounted upon said frame; said support and

- riveting device being mounted upon opposite sides of said abutment member; a manually operated valve for controlling the flow of fluid to said means for actuating the 5 work-support and riveting device; a separate valve for controlling the flow of such fluid to said riveting device; and means for automatically controlling the last-named valve.
- 10 7. In a riveting machine, the combination of a suitable frame; an abutment member secured to the latter; a riveting tool mounted in and projecting through said abutment member; a work-holder movable 15 toward and from said member and in alinement with said tool; a riveting device mounted upon said frame and at the side of said abutment member opposite that at which said work-holder is mounted; and 20 means for controlling the movement of said holder and operation of said riveting device.
8. In a riveting machine, the combination of a suitable frame; a pneumatic riveting device mounted upon said frame and provided 25 with a controlling valve; a pneumatically operated work-holder in alinement with said riveting device and movable toward and from said device; an abutment member secured to said frame intermediately 30 of said riveting device and said holder; a riveting tool mounted in said member projecting therethrough and alined with said riveting device and said holder; said device being adapted to engage one side of said 35 tool and the work when supported by said holder being adapted to engage the other side thereof; and a strap fixed with relation to said frame and lying in the path of yielding movement of said controlling valve.
- 40 9. In a riveting machine, the combination of a suitable frame; a pneumatically-operated hammer mounted upon said frame and so as to yield in the direction of its axis; and provided with a controlling valve and 45 lever therefor; a pneumatically-operated work-holder alined with said hammer; an abutment member secured to said frame in- 50 termediately of said hammer and work-holder; a loosely-mounted riveting tool carried by and projecting through said member and alined with said hammer and holder; a strap fixed with relation to said frame and lying in the path of yielding movement of said controlling valve lever; and a second valve controlling the operation 55 of said work-holder and hammer.
10. In a riveting machine, the combination of a suitable frame; a vibratory hammer mounted upon said frame; a work-holder movable toward and from said hammer; an abutment member secured to said frame intermediately of said hammer and holder; a riveting tool movably mounted in 60 said member, projecting therethrough and in alinement with said hammer and holder; 65 and spring mechanism for holding the head of the hammer in engagement with the head of said tool.
11. In a riveting machine, the combination of a suitable frame; an abutment-member 70 mounted upon the latter; a work-support relatively movable toward and from said abutment-member; a riveting device coöperating with said work-support; means for controlling the operation of said riveting 75 device; and means for positively actuating and controlling the relative movement of said work-support.
12. In a riveting machine, the combination of a suitable frame; an abutment-member 80 fixed to and adjustable upon the latter; a work-support relatively movable toward and from said abutment-member; a riveting device mounted upon said frame and coöperating with said work-support; means for 85 controlling the operation of said riveting device; means for positively effecting the relative movement of said work-support; and means for controlling such latter actuation. 90

Signed by us, this 20th day of July, 1915.
